Primary Examiner — Susan Bennett Hattan*Assistant Examiner* — Leanne Was(74) *Attorney, Agent, or Firm* — Yen T. Florczak(57) **CLAIM**

The ornamental design for a bollard luminaire window, as shown and described.

DESCRIPTION

FIG. 1 is a perspective view showing the new design for a bollard luminaire window;

FIG. 2 is a front view thereof;

FIG. 3 is a side view thereof;

FIG. 4 is a top view thereof;

FIG. 5 is a magnified view of the perspective view of FIG. 1 thereof;

FIG. 6 is a magnified view of the front view of FIG. 2 thereof; and,

FIG. 7 is a perspective mirror image view thereof, positioned in a bollard luminaire.

The broken lines in the drawings depict environmental subject matter only and form no part of the claimed design.

1 Claim, 3 Drawing Sheets(56)
